UNITED STATES PATENT OFFICE.

JOHN A. HOLZAPFEL, OF JACKSON, MICHIGAN.

ANCHOR-ROPE PULLEY.

Application filed February 12, 1923. Serial No. 618,542.

To all whom it may concern:

Be it known that I, JOHN A. HOLZAPFEL, a citizen of the United States, residing at the city and county of Jackson, State of Michigan, have invented certain new and useful Improvements in Anchor-Rope Pulleys, of which the following is a specification.

This invention relates to improvements in anchor rope pulleys.

The main objects of this invention are:

First, to provide an improved anchor rope pulley adapted to wring the water from the rope as it is hauled in and also one which is well adapted for manipulation from various positions in the boat.

Second, to provide an improved anchor rope pulley which may be mounted in various positions on various parts of a boat and the anchor rope manipulated from different positions to suit the convenience of the operator.

Further objects, and objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a plan view of an anchor rope wringer embodying the features of my invention, the pulley block being shown in one position by full lines and in another position by dotted lines.

Fig. II is a side elevation.

Fig. III is a vertical section on a line corresponding to line 3—3 of Figs. I and IV.

Fig. IV is a detail section on a line corresponding to line 4—4 of Figs. II, III and V.

Fig. V is a detail section on a line corresponding to line 5—5 of Figs. II and IV.

In the drawing the sectional views are taken looking in the direction of the little arrows at the ends of the section lines and similar numerals of reference refer to similar parts throughout the several views.

Referring to the drawing, I provide a pulley block designated generally by the numeral 1, and comprising a pair of spaced

side plates between which the pulleys 2, 3 and 4 are journaled, the journal 5 of the pulley 3 being supported in slots 6 so that the pulley 3 may move relatively to the pulley 2. The pulley 4 is disposed at the rear of and below the pulley 3 so that the anchor rope as 7 may be passed between the pulleys 2 and 3, over the pulley 3 and under the pulley 4. With the pulleys thus arranged, a hauling pull on the rope forces the pulley 3 toward the pulley 2, thereby securing the wringing action.

To provide means for supporting the pulley upon a boat to permit its convenient operations from different positions in the boat, I provide a base 8 having a depending bracket arm 9 at one side adapted to engage a part of the boat as 10, and a clamping screw 11 carried by the depending arm 12 opposed to the arm 9. This permits of the mounting of the base as may be desired.

The base is provided with an inclined bearing surface 13 for the pulley block, the bearing surface having an elongated bearing opening 14 therein for the bearing stud 15. The bearing stud has an elongated head 16 which may be introduced through the elongated opening 14 when the head is presented longitudinally thereto, but constitutes a retaining member when turned transversely thereof as indicated in Figs. IV and V.

The base member is provided with a segmental bearing way 17, the stud 15 being positioned centrally relative to this segmental way. The pulley block has a downwardly offset arm 18 engaging the under side of this way 17 and coacting with the stud 15 in supporting the pulley block for oscillating movement. A pin 19 on the arm 18 coacts with stop portions 20 at the ends of the way, preventing the arm swinging out of engagement with the way. The pulley 4 is located at the rear of the bearing stud and the pulley block so that a hauling pull upon the rope 7 swings the pulley block in the direction of the pull.

With this arrangement of parts the device may be mounted, as desired, on the side or at either end of the boat and the operator may manipulate the rope from any convenient position with a minimum of binding or snubbing effect, owing to the pulley block swinging into the proper position. The structure is also desirable for use where the base is permanently secured.

to some portion of the boat as by means of screws.

I have illustrated and described my improvements in an embodiment which I have found very satisfactory. I have not attempted to illustrate or describe certain modifications which might be desirable, as I believe the disclosure made will enable those skilled in the art to which my invention relates to embody or adapt the same as may be desired.

Having thus described my invention what I claim as new and desire to secure by Letters Patent is:

15. 1. In a structure of the class described, the combination with a pulley block provided with a pair of coacting wringer pulleys, one of which is movably mounted relative to the other, and with a guide pulley disposed at the rear of said wringer pulleys, of a base member provided with attaching means and having a segmental way and a bearing surface for said pulley block, said bearing surface having an elongated bearing opening therein disposed centrally relative to said way, a bearing stud on said pulley block coacting with said bearing opening and having an elongated head adapted to be engaged and disengaged with said bearing opening when presented longitudinally thereto and constituting a retaining member when turned transversely thereof, the said guide pulley being disposed at the rear of said bearing stud, a downwardly offset arm on the rear end of said pulley block coacting with the under side of said segmental way, and a retaining pin on said arm, said base member being provided with coacting stops at the ends of said way.
2. In a structure of the class described, the combination with a pulley block provided with a pair of coacting wringer pulleys, one of which is movably mounted relative to the other and with a guide pulley disposed at the rear of said wringer pulleys, of a base member provided with attaching means and having a segmental way and a bearing surface for said pulley block, said bearing surface having an elongated bearing opening therein disposed centrally relative to said way, a bearing stud on said pulley block coacting with said bearing opening and having an elongated head adapted to be engaged and disengaged with said bearing opening when presented longitudinally thereto and constituting a retaining member when turned transversely thereof, the said guide pulley being disposed at the rear of said bearing stud, a downwardly offset arm on the rear end of said pulley block coacting with the under side of said segmental way, and a retaining pin on said arm, said base member being provided with coacting stops at the ends of said way.
3. In a structure of the class described, the combination with a pulley block, of a base member provided with attaching means

and having a segmental way and a bearing surface for said pulley block, said bearing surface having an elongated bearing opening therein disposed centrally relative to said way, a bearing stud on said pulley block coacting with said bearing opening and having an elongated head adapted to be engaged and disengaged with said bearing opening when presented longitudinally thereto and constituting a retaining member 75 when turned transversely thereof, a downwardly offset arm on the rear end of said pulley block coacting with the under side of said segmental way, and a retaining pin on said arm, said base member being 80 provided with coacting stops at the ends of said way.

4. In a structure of the class described, the combination with a pulley block, of a base member provided with attaching 85 means and having a segmental way and a bearing surface for said pulley block, said bearing surface having an elongated bearing opening therein disposed centrally relative to said way, a bearing stud on said pulley block coacting with said bearing opening and having an elongated head adapted to be engaged and disengaged with said bearing opening when presented longitudinally thereto and constituting a retaining member 95 when turned transversely thereof, and an offset arm on the rear end of said pulley block coacting with said segmental way.

5. In a structure of the class described, the combination with a pulley block provided with a pair of coacting wringer pulleys, and with a guide pulley disposed at the rear of said wringer pulleys, of a base member provided with attaching means and having a segmental way and a bearing opening disposed centrally relative to said way, a bearing stud on said pulley block coacting with said bearing opening, the said guide pulley being disposed at the rear of said bearing stud, a downwardly offset arm on the rear end of said pulley block coacting with the under side of said segmental way, and a retaining pin on said arm, said base member being provided with coacting stops at the ends of said way.

6. In a structure of the class described, the combination with a pulley block provided with a pair of coacting wringer pulleys and with a guide pulley disposed at the rear of said wringer pulleys, of a base member provided with attaching means and having a segmental way and a bearing opening disposed centrally relative to said way, a bearing stud on said pulley block coacting with said bearing opening, the said guide pulley being disposed at the rear of said bearing stud, and an arm on the rear end of said pulley block coacting with said segmental way.

7. In a structure of the class described, the combination with a base member provided with attaching means and having a segmental way at the rear thereof, and a pulley block pivotally mounted on said base member centrally of said way and having a part engaging said way whereby the pulley block is supported on the base for oscillating movement thereon, said pulley block being provided with a guide pulley located at the rear of its pivot.

8. In a structure of the class described, the combination of a base member provided with an attaching means and having a segmental way and a bearing opening disposed centrally relative to said way, a pulley block superimposed upon said base member and provided with a bearing stud coacting with said bearing opening and with a downwardly offset arm on its rear end coacting with the under side of said segmental way, said pulley block being provided with a pulley disposed above said bearing stud and with a guide pulley disposed at the rear thereof.

25 9. In a structure of the class described, the

combination of a base member provided with an attaching means and having a segmental way and a bearing opening disposed centrally relative to said way, a pulley block superimposed upon said base member and provided with a bearing stud coacting with said bearing opening and with a downwardly offset arm on its rear end coacting with the under side of said segmental way, said pulley block being provided with a pulley disposed above said bearing stud.

10. In a structure of the class described, the combination of a base member having a segmental way and a bearing opening disposed centrally relative to said way, a pulley block superimposed upon said base member and having a bearing stud engaging said bearing opening and an arm engaging said way, said pulley block being provided with a rope guide member at the rear of the bearing stud.

In witness whereof, I have hereunto set my hand and seal.

JOHN A. HOLZAPFEL. [L.S.]
